UNITED STATES PATENT OFFICE.

THOMAS JAMES KENNEDY, OF RENFREW, PENNSYLVANIA.

RAIL-JOINT.

SPECIFICATION forming part of Letters Patent No. 482,796, dated September 20, 1892.

Application filed May 7, 1892. Serial No. 432,190. (No model.)

To all whom it may concern:

Be it known that I, THOMAS JAMES KENNEDY, a citizen of the United States, residing at Renfrew, in the county of Butler and State 5 of Pennsylvania, have invented a new and useful Rail-Joint, of which the following is a specification.

The invention relates to improvements in rail-joints.

10 The object of the present invention is to simplify and improve the construction of rail-joints, and to provide one which may be readily applied to rails and which will securely hold them in proper position.

15 The invention consists in the construction and novel combination and arrangement of parts hereinafter fully described, illustrated in the accompanying drawings, and pointed out in the claims hereto appended.

20 In the drawings, Figure 1 is a perspective view of a rail-joint constructed in accordance with this invention. Fig. 2 is a transverse sectional view. Fig. 3 is a detail perspective view of the base-plate. Fig. 4 is a similar 25 view of the removable inner fish-plate.

Like numerals of reference indicate corresponding parts in all the figures of the drawings.

1 designates a base-plate adapted to support 30 the meeting ends of rails 2 and forming a flat seat for the same and provided at its outer end with an integral outer fish-plate 3, between which and a removable inner fish-plate 4 the rails 2 are clamped. The outer 35 fish-plate conforms to the configuration of the rails and consists of a vertical and an inclined portion, and its inclined portion forms, with the base-plate, a recess to receive the bottom flanges of the rails. The inner fish-plate consists of a vertical and an inclined portion, and 40 it is provided on its lower face with lugs 5, which have their outer ends beveled and adapted to interlock with similarly-constructed lugs 6 on the upper face of the inner end of 45 the base-plate. The lugs are arranged at regular intervals, and the intervals between the lugs are the same width as the lugs, whereby in placing the removable fish-plate in position its lugs may be inserted in the intervals

between the lugs 6 of the base-plate, and after 50 the removable fish-plate is in contact with the rails it may be moved longitudinally to cause the lugs to interlock. The removable fish-plate is held against longitudinal movement to prevent its becoming accidentally 55 unlocked by wedges 7, which when the removable fish-plate 4 is in proper position and the lugs are interlocked are driven in the intervals or spaces between the lugs. The base-plate is provided at its end with spike- 60 recesses 8, adapted to receive spikes for securing the base-plate to a cross-tie. The wedges, besides holding the inner fish-plate against longitudinal movement, also cause it to clamp 65 the rails.

What I claim is—

1. A rail-joint comprising a base-plate forming a seat for rails and provided at one end with an integral fish-plate and having at its other end lugs arranged at intervals and 70 having their inner ends beveled, a removable fish-plate provided on its lower face with lugs having their outer ends beveled and arranged at intervals and adapted to interlock with the lugs of the base-plate, and means 75 for holding the lugs in engagement, substantially as described.

2. A rail-joint comprising a base-plate forming a seat for rails and provided at one end with an integral fish-plate and having at 80 its other end lugs arranged at intervals and having their inner ends beveled, a removable fish-plate provided on its lower face with lugs having their outer ends beveled and arranged at intervals and adapted to interlock 85 with the lugs of the base-plate, and wedges arranged in the intervals or spaces between the lugs and holding the removable fish-plates against longitudinal movement and causing the same to clamp rails, substantially as de- 90 scribed.

In testimony that I claim the foregoing as my own I have hereto affixed my signature in the presence of two witnesses.

THOMAS JAMES KENNEDY.
